UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

FILLING-END CATCHER FOR LOOMS.

1,331,675.

Specification of Letters Patent. Patented Feb. 24, 1920.

Application filed October 12, 1918. Serial No. 257,870.

To all whom it may concern:

Be it known that I, ALONZO E. RHOADES, a citizen of the United States, and resident of Hopedale, county of Worcester, State of Massachusetts, have invented an Improvement in Filling-End Catchers for Looms, of which the following description, in connection with the accompanying drawing, is a specification, like characters on the drawing

10 representing like parts.

This invention relates to improvements in automatic filling replenishing looms in which means are provided for catching the trailing end of the filling which extends 15 from the shuttle to an abandoned filling carrier as it is discharged from the shuttle by the transferring mechanism and the object thereof is to provide means for pivotally supporting the filling end catcher which will 20 permit it to swing aside if an obstruction is caught between it and a moving part of the loom to avoid a smash.

Another object of the invention is to provide spring actuated means for supporting 25 the filling end catcher which will permit it to move bodily in parallelism with the lay and which will also permit it to have a swinging movement independent of said bodily movement.

30 More specifically the object of the invention is to provide means for supporting a filling end catcher from the usual transerrer stud which will enable it to rock bodily about the axis of said stud and which will 35 also permit it to swing yieldably either forwardly or rearwardly if an obstruction is caught between it and the lay or some other moving part of the loom.

A further object of the invention is to 40 provide a rigid construction for catching the trailing filling end which will be capable of a plurality of yieldable movements which will prevent the likelihood of breakage of any of the parts by obstructions caught between the filling end catcher and a moving 45 part of the loom.

Other objects and features of the invention will more fully appear from the following description and the accompanying 50 drawings and will be pointed out in the following claims.

In the drawings;

Figure 1 is a side elevation of a portion of the battery end of a loom of the Northrop

type illustrating my invention applied thereto,

Fig. 2 is a detail plan view of a preferred embodiment of my invention showing the same as supported upon an extension of the usual transerrer stud,

Fig. 3 is an end elevation of the loom illustrated in Fig. 1, partly in vertical section,

Fig. 4 is a detail view partly in section showing the means by which the filling end 65 catcher is pivotally supported from the transerrer stud, and,

Fig. 5 is a view partly in section showing the means for yieldably supporting the filling end catcher to enable it to swing for- 70 wardly or backwardly.

In the operation of automatic filling re-plenishing looms when transfer takes place the filling running to the filling carrier about to be discharged is usually severed ad- 75 jacent the nose of the shuttle and when the abandoned filling carrier is discharged from the shuttle a trailing end is left which runs from the eye of the shuttle to the abandoned filling carrier. If this trailing end is not 80 removed before the next pick succeeding transfer the filling end is likely to be drawn into the cloth and form an imperfection in the weave.

Means have therefore been provided for 85 catching this trailing end of the filling and usually comprise a device positioned beneath the aperture in the lay through which the filling carrier is discharged and behind the path of the filling carrier as it is discharged 90 from the shuttle so that as the lay recedes the trailing filling end will be drawn over the filling end catcher and drawn from the shuttle.

In some instances a delayed movement of 95 the picker stick may encounter the filling end catcher as the lay moves forward or a filling carrier may drop between the filling end catcher and the lay or some other moving part of the loom which will cause a 100 smash.

The object of the present invention there-fore is to provide means which will permit a bodily movement of the filling end catcher and also a supplemental swinging move- 105 ment which under any condition will prevent a smash.

Inasmuch as the present invention is ad-

dressed to improvements in mechanism for supporting the filling end catcher the particular construction or the general features of the loom to which it is applied are unimportant. For convenience in illustration a preferred embodiment of the invention is shown as applied to an automatic filling replenishing loom of the well known Northrop type. In this type of loom the frame or loom side 1 supports, at the transfer end of the loom, a hopper stand 2 upon which is mounted a rotary hopper 3 which carries a circular series of fresh filling carriers 4. The stand 2 has the usual transerrer stud 5 upon which the transerrer 6 is pivotally mounted, the transerrer being provided with the usual dog 7 which upon call for filling replenishment is elevated into the path of the bunter 8 upon the lay 9 and is actuated thereby to cause the transerrer to thrust a fresh filling carrier into the shuttle and knock out the abandoned filling carrier therefrom.

The lay 9 has the usual shuttle box 10 and the shuttle box and lay are provided with a vertical aperture 11 through which the filling carrier is discharged by the transerrer. A chute 12 carried by an arm or bracket 13 secured to the end of the lay 10 by means including a bolt 14 serves to direct the abandoned filling carrier 15 into the usual box or receptacle.

In the preferred embodiment of the invention illustrated herein I have provided means for supporting the filling end catcher from the usual transerrer stud in such a manner that the filling end catcher may rock bodily about said stud.

The filling end catcher in the construction shown herein is in the form of a flat plate 16 having a serrated upper edge 17 to engage the filling and is secured to a laterally extending portion 18 of a supporting arm 19 which has intermediate of its length a downwardly projecting stud 20 which is journaled in a boss 21 at the end of a bracket 22.

The bracket 22 is pivotally connected by a bolt 23 to the lower end of an arm 24 which is mounted to swing about the axis of the transerrer stud 5. By reason of the pivotal connection between the bracket 22 and the arm 24, the filling end catcher 16 may be raised or lowered into any desired position relative to the path of the shuttle.

The arm 24 may be pivoted directly upon the transerrer stud but preferably is mounted upon an extension of smaller diameter, such as a stud 25, extending into a socket in the end of the transerrer stud and secured therein by a set screw 26.

Any suitable means may be provided for yieldably supporting the arm 24 to permit it to swing bodily if the filling end catcher is engaged by the wall of the aperture in the lay or by an obstruction such as the

picker stick when delayed in its movement or an obstruction caught between the lay and the filling end catcher. A preferred means for thus yieldably supporting the arm 24 comprises a helical spring 27 which surrounds the stud 25 and is anchored at one end 28 in said arm and at the other end in a sleeve 30 secured to the stud 25 by a set screw 31. The sleeve 30 preferably has a hollow barrel 32 providing an inclosing chamber for the spring 27.

The spring 27 acts to swing the arm rearwardly and upwardly but its movement may be limited by the engagement of a lug 32' projecting from the arm 24 with the rear wall of a recess 33 in a collar 34 secured upon the stud 25. The recess 33 may be of any desired size to permit sufficient amplitude of movement of the arm 24. By rotarially adjusting the collar 34 the filling end catcher may be positioned properly in respect to the path of the discharged filling carrier. Preferably it is positioned to lightly engage the rear wall of the aperture 11 when the lay reaches the limit of its forward movement, at which position transfer is effected. The abandoned filling carrier will then pass in front of the filling end catcher and as the lay recedes the trailing filling end will be drawn across and caught by its serrated edge and thereby pulled from the shuttle eye.

Occasionally the picker stick is delayed in its action and comes between the lay and the filling end catcher as the lay moves forward but the smash which might result is avoided by the yieldability of the arm 24 about the stud 25.

Other conditions may however arise which might cause a smash as by the premature dropping of a filling carrier between the rear wall of the aperture in the lay and the filling end catcher, or by a filling carrier or other obstruction being caught between the dog on the transerrer or some other moving part of the loom and the filling end catcher. In order to avoid such a result, and to give greater amplitude of movement to the filling end catcher under such abnormal circumstances I have mounted the filling end catcher in such manner that it may yield either forwardly or rearwardly if an obstruction is caught between it and a moving part of the loom.

In the preferred mechanism illustrated herein the forward end 37 of the arm 19 which supports the filling end catcher is provided with a slot 38 through which extends a stud 39 which is rigidly secured at one end in a boss 40 in the bracket 22, helical springs 41 and 42 mounted upon the stud and pressing equally upon opposite sides of the end 37 of the arm 19 serving to maintain the arm in a central position normal to the lay so that the filling end

catcher will be held in parallelism with the rear wall of the aperture 11.

The spring 41 engages at one end the boss 40 and at the other a washer 43 which 5 covers the slot 38 while the other spring 42 engages a similar washer 44 covering the other side of the slot and abuts at its opposite end against a collar 45 which is held upon the stud 39 by a cotter pin 46 or other 10 suitable fastening means. A collar 47 secured to the stud 39 insures the central position of the arm under the action of the springs 41 and 42.

In order to prevent dust, lint and other 15 substances from being deposited upon the springs 41 and 42 and thus interfering with their efficiency and the freedom of movement of the arm 19 a guard plate 48 is provided which overlies and partially incloses 20 the springs and the pivotal support for the arm 19. This plate is provided with an upwardly extending flange 49 which is riveted or otherwise secured to the bracket 22.

By thus pivotally supporting the arm 24 25 so that it may be yieldably rocked about the horizontal axis of the transerrer stud and also providing means whereby the filling end catcher may yieldably swing forwardly or backwardly about a vertical pivot sufficient 30 flexibility of movement is given to the filling end catcher to enable it under all conditions to yield sufficiently to avoid smashes, while the construction is of such a rigid character that the likelihood of breakage or 35 wear is reduced to a minimum.

It will be understood that the embodiment 40 of the invention disclosed herein is illustrative and not restrictive and that various modifications may be made in construction and arrangement of parts within the meaning and scope of the following claims.

Having thus described my invention what I claim as new and desire to secure by Letters Patent is;

45 1. In a filling replenishing loom comprising a lay provided with an aperture therethrough to permit the discharge of an abandoned filling carrier, a filling end catcher positioned below the shuttle and behind the 50 path of the filling carrier during filling replenishment to engage the trailing filling end as the lay recedes having yieldable supporting means acting to permit forward bodily movement of said filling end catcher 55 and pivotal means to permit a forward swinging movement thereof about a vertical axis whereby a smash will be prevented if an obstruction is caught between the filling end catcher and the lay as the latter 60 beats up.

65 2. In a filling replenishing loom comprising a lay provided with an aperture therethrough to permit the discharge of an abandoned filling carrier, a filling end catcher positioned below the shuttle and behind the

path of the filling carrier during filling replenishment to engage the trailing filling end as the lay recedes having yieldable supporting means acting to permit forward bodily movement of said filling end catcher 70 and means to permit a rearward swinging movement about a vertical axis thereof whereby a smash will be prevented if an obstruction is caught between said filling end catcher and a moving part of the loom. 75

3. In a filling replenishing loom comprising a lay provided with an aperture therethrough to permit the discharge of an abandoned filling carrier, a filling end catcher positioned below the shuttle and behind the 80 path of the filling carrier during filling replenishment to engage the trailing filling end as the lay recedes having yieldable supporting means acting to permit forward bodily movement of said filling end catcher 85 and means to permit both forward and rearward swinging movements of said filling end catcher whereby a smash will be prevented if an obstruction is caught between the filling end catcher and a moving part of 90 the loom.

4. In a filling replenishing loom comprising a lay provided with an aperture therethrough to permit the discharge of an abandoned filling carrier, a filling end catcher 95 positioned below the shuttle and behind the path of the discharged filling carrier during replenishment, yieldable means pivotally supporting said filling end catcher acting to permit the same to swing bodily forward on a horizontal axis in parallelism with the lay and supplemental supporting means acting to permit said filling end catcher to swing independently of said bodily movement whereby a smash will be 100 prevented if the discharged filling carrier or other obstruction is caught between said filling end catcher and a moving part of the loom.

5. In a filling replenishing loom comprising a lay having an aperture therethrough to permit the discharge of an abandoned filling carrier, a hopper, a hopper stand provided with a laterally extending transerrer stud and a transerrer mounted thereon operable by the forward movement of the lay upon call for filling replenishment, a filling end catcher, means for supporting said filling end catcher comprising an arm pivotally mounted upon said stud, a helical spring surrounding said stud and anchored at its ends respectively to said arm and to said stud acting to hold the filling catcher in a position below the shuttle and behind the path of the discharged filling carrier during replenishment and means for limiting the rearward movement of said filling end catcher. 115

6. In a filling replenishing loom comprising a lay having an aperture therethrough to permit the discharge of an abandoned filling 120

carrier, a hopper and a hopper stand provided with a laterally extending transferrer stud, a transferrer mounted thereon operable by the forward movement of the lay 5 upon call for filling replenishment, an arm pivotally mounted upon said transferrer stud to rotate about a horizontal axis, a filling end catcher pivotally mounted upon said arm to swing about a vertical axis, 10 yieldable means normally acting to hold said filling end catcher in a position below the shuttle and behind the path of the discharged filling carrier and in parallelism with the rear wall of the aperture of the 15 lay whereby the filling end catcher is permitted to yield bodily and to swing about its vertical pivot if an obstruction is caught between it and a moving part of the loom.

7. In a filling replenishing loom comprising a lay having an aperture therethrough 20 to permit the discharge of an abandoned filling carrier, a hopper and a hopper stand provided with a laterally extending transferrer stud and a transferrer mounted thereon 25 operable by the forward movement of the lay upon call for filling replenishment, a depending arm pivotally and yieldably mounted upon said transferrer stud, a bracket carried by said arm, a filling end 30 catcher for a support pivot upon said bracket, and resilient means carried by said bracket engaging said support and tending

normally to maintain said filling end catcher in parallelism with the lay but permitting the same to swing out of parallelism with 35 the lay if an obstruction is caught between the filling end and a moving part of the loom.

8. In a filling replenishing loom comprising a lay having an aperture therethrough 40 to permit the discharge of an abandoned filling carrier, a hopper and a hopper stand provided with a laterally extending transferrer stud, a transferrer mounted thereon operable by the forward movement of the 45 lay upon call for filling replenishment, a depending arm pivotally and yieldably mounted upon said transferrer stud, a bracket carried by said arm, a filling end catcher for a support pivot upon said 50 bracket, a filling end catcher having a support pivot between its ends upon said bracket, springs carried by said bracket engaging opposite sides of the pivot support for said filling end catcher and normally 55 acting to maintain said filling end catcher in parallelism with the lay but capable of yielding in either direction if an obstruction is caught between the filling end catcher and a moving part of the loom. 60

In testimony whereof I have signed my name to this specification.

ALONZO E. RHOADES.
